UNITED STATES PATENT OFFICE.

WILLIAM McCLAVE, OF SCRANTON, PENNSYLVANIA, ASSIGNOR TO McCLAVE-BROOKS COMPANY, OF SCRANTON, PENNSYLVANIA, A CORPORATION OF PENNSYLVANIA.

GRATE.

No. 849,914.

Specification of Letters Patent.

Patented April 9, 1907.

Application filed September 6, 1906. Serial No. 333,485.

To all whom it may concern.

Be it known that I, WILLIAM McCLAVE, a citizen of the United States, residing at Scranton, in the county of Lackawanna and State of Pennsylvania, have invented certain new and useful Improvements in Grates; and I do hereby declare the following to be a full, clear, and exact description of the invention, such as will enable others skilled in the art to which it appertains to make and use the same.

This invention relates to improvements in grates, and more particularly to the journal-bearing bars thereof.

15 The object in view is the provision of means for facilitating the ready positioning of the journal of a grate-bar in the bearing of the journal-bearing bar and the effectual retention thereof without the employment of 20 wedges or other auxiliary locking devices.

With these and other objects in view the invention comprises certain novel constructions, combinations, and arrangements of parts, as will be hereinafter fully described 25 and claimed.

In the accompanying drawings, Figure 1 is a longitudinal vertical section through a furnace structure, the grate-bars being omitted and a journal-bearing bar being illustrated 30 in elevation. Fig. 2 is a view of a fragment of the journal-bearing bar seen in elevation. Fig. 3 is a similar view of the same with the sectional journal-caps removed. Fig. 4 is a top plan view of a fragment of the bar. Fig. 35 5 is an inverted plan view of the sectional cap.

In carrying out the invention the journal-bar 1 is formed with as many journal-bearings 2 as are required for accommodating the journal ends of the grate-bars, and the journal-bearing bar is formed with an opening 3, leading through the upper edge of the bar of each bearing 2, so that the journal of the grate-bar may be dropped readily into the bearing. It is of course desirable to prevent vertical play of the bar, and to accomplish this result I propose to employ a sectional locking-cap, which may be readily positioned for closing the opening 3 and may as readily be removed, if desired. Furthermore, this invention contemplates the production of a cap which does not necessitate the use of key-plugs or wedges at any time, each cap for each journal-bearing consisting simply of the two sections 4 and 5. The

journal-bearing bar 1 at each side of each opening 3 is formed with inclined recesses 6, leaving a central web 7, and each of the sections 4 and 5 is bifurcated, so as to fit snugly over the respective web 7 and be held thereby against lateral play. The section 5 is formed with an overhanging portion 5', which is preferably curved to conform to the curvature of the journal, and the upper end of the section 5 is beveled off in such manner that the upper end of the section 4 overhangs 65 the beveled portion of the section 5 and snugly contacts therewith, so that the section 5 cannot be moved upwardly when in position without also moving the section 4 upwardly. The recesses 6 are arranged approximately at right angles, and the incline of said recesses of course results in the lower ends of the recesses being farther apart than the upper ends, and hence the lower bifurcated ends of the sections 4 and 5 are spread 70 apart, while the upper end of the section 4 overlaps the section 5, and therefore any pressure exerted on the overhanging portion 75 5' of section 5 will tend to draw both sections 4 and 5 upwardly, which operation is impossible in view of the fact that the lower ends 80 of the sections are farther apart than the width of the opening 2 at its upper end. In other words, the overhanging walls produced by the recesses 6, against which the outer 85 edges of the bifurcated sections 4 and 5 contact, prevent vertical movement of the said sections 4 and 5, the only movement which is permitted being the movement longitudinal with respect to the particular section, and 90 as section 4 overlaps section 5 section 5 cannot be removed until section 4 has been removed, and this later operation cannot be accomplished by any pressure exerted by the journal against the overhanging portion 5'. 95 It is thus to be observed that the sectional caps not only form a closure for the journal-bearing, but form an effectual lock for preventing the journal from lifting, and the locking action is accomplished without the aid of 100 any auxiliary devices.

By preference the lower end of each of the recesses 6 is beveled outwardly, as at 8, below the termination of the bifurcated end of the respective sections 4 and 5. This facilitates the introduction of a tool beneath the respective section for driving the section upwardly should the same become firmly fixed 105

in place through rusting or expansion or from other causes. It is of course well known that the bearing-bar expands at its upper edge to a greater extent than at its lower edge, owing to the intense heat at the upper edge, and this difference of expansion will result in warping unless provision is made against the same, so that heretofore provision has been made for such expansion by the use of a loosely-fitting cap for the journal and a wedge for locking same in place. As I employ no wedge in connection with my journal-cap, but instead employ simply a sectional cap, I contemplate forming a notch or mesh 9 in the journal-bearing bar between each two of the journals 2, so that the upper edge of the journal-bearing bar may expand freely longitudinally in spite of the fact that the sectional cap fits snugly in place. At the lower end of the notch 9 by preference the material of the journal-bearing bar is beveled in opposite directions from the central point, so that ashes or other foreign material falling into the notch 9 will be directed to one side.

I claim—

1. In a grate structure, the combination with a journal-bearing bar formed with a bearing and an opening leading therefrom to the upper edge of the bar, the bar being formed with a recess at each side of the opening inclined toward the opening, and a sectional cap for closing said opening, the sections of the cap engaging the said recesses and extending across the opening.

2. In a grate structure, the combination with a journal-bearing bar formed with a bearing and an opening leading therefrom to that portion of the bar designed to be subjected to the greatest amount of heat, recesses being formed in the material of the bar at the sides of the opening, said recesses being inclined and extending toward the outer portion of the opening, a grate-bar formed with a journal engaging the bearing of said journal-bearing bar, and a sectional cap having its sections engaging the said recesses and extending into said opening to retain the journal in its operative position.

3. In a grate structure, the combination with a journal-bearing bar formed with a bearing and an opening extending therefrom to the edge of the bar, the material of the bar at the sides of the opening being recessed and the recesses having their longitudinal axes disposed in planes converging in a direction toward the edge of the bar, a grate-bar formed with a journal engaging said bearing, and a sectional cap having its sections engaging the said recesses and extending beyond the same into said opening for retaining the journal in its operative position.

4. In a grate structure, the combination with a journal-bearing bar having a journal-bearing, and an opening extending from said

bearing to the edge of the bar, of a sectional cap for closing said opening, the sections of the cap being arranged to extend in inclined planes and one of the sections to overlap the other.

5. In a grate structure, the combination with a journal-bearing bar having a journal-bearing, and an opening extending therefrom to the edge of the bar and formed with recesses on both sides of said opening, of a sectional cap formed of overlapping sections adapted to be locked in position by engagement with said recesses.

6. In a grate structure, the combination with a journal-bearing bar formed with a bearing, and an opening extending therefrom to the edge of the bar, of a sectional cap for closing said opening, one of the sections of the cap engaging a portion of the bar for being retained in position and the other section of the cap engaging the first-mentioned section of the cap and also engaging a portion of the bar for being retained in position.

7. In a grate structure, the combination with a journal-bearing bar having a journal-bearing, and an opening extending therefrom to the edge of the bar, and inclined recesses arranged at the sides of the opening, of a sectional cap formed with overlapping sections engaging said inclined recesses.

8. In a grate structure, the combination with a journal-bearing bar, having a journal-bearing and an opening extending therefrom to the edge of the bar, of a sectional cap for closing said opening, one of said sections overlapping the other, and means formed integral with the bar and coacting with the overlapping section for locking the cap in position.

9. In a grate structure, the combination with a journal-bearing bar having a bearing, and an opening leading therefrom to the edge of the bar, of a sectional cap for closing said opening, one section of the cap overlapping the other and the sections of the cap bearing angular relation with respect to each other, and means formed integral with the bar for preventing simultaneous removal of the sections of the cap.

10. In a grate structure, the combination with a journal-bearing bar having a journal-bearing, and an opening leading therefrom to the edge of the bar, said bar being formed with undercut portions contiguous to said bearing, of a sectional cap for closing the opening, one of the sections of said cap engaging one of the undercut portions, and the other section of the cap overlapping the first section of the cap and engaging the other undercut portion.

11. In a grate structure, the combination with a journal-bearing bar having a journal-bearing, and an opening leading therefrom to the edge of the bar, the said bar being formed with undercut portions contiguous to

the journal-bearing, of a sectional cap for closing the said opening, one section of said cap engaging one of the undercut portions and having an overhanging portion above 5 the journal-bearing, and the other section of the cap engaging the other undercut portion and extending above the overhanging portion of the first-mentioned section.

12. In a grate structure, the combination 10 with a journal-bearing bar having a journal-bearing and formed with an opening leading from said bearing to the edge of the bar, the said bar being provided with an inclined recess in each face at each side of the bearing 15 leaving an intermediate web, of a sectional cap for closing said opening, the sections of said cap being bifurcated and positioned for inclosing the respective webs one of the sections of the cap overlapping the other.
13. In a grate structure, the combination 20

with a journal-bearing bar having a journal-bearing and formed with an opening leading from said bearing to the edge of the bar, the said bar being provided with an inclined recess in each face at each side of the bearing 25 leaving an intermediate web, of a sectional cap for closing said opening, each section of said cap being bifurcated and positioned for inclosing the respective web, the recesses being beveled off below the bifurcated ends of 30 the sections of the cap for exposing said ends for facilitating the application of a removing tool.

In testimony whereof I affix my signature in presence of two witnesses.

WILLIAM McCLAVE.
